COMBINED TUBING DRAIN AND JAR

John S. Page, Long Beach, Calif., assignor to Page
Oil Tools Inc., Long Beach, Calif., a corpora-
tion of California

Application April 21, 1947, Serial No. 742,939

4 Claims. (Cl. 137—739)

1

This invention relates to a combined tubing drain and jar and it is a general object of the invention to provide a simple, effective and dependable structure for use in connection with tubing employed in a well.

It is common to produce a well through tubing, in which case the lower end portion of the tubing string is usually secured in the well casing by means of a tubing anchor. Tubing is usually employed to carry a pump and in practice it is occasionally necessary to remove or withdraw the tubing from the well, in which case it is highly advantageous to have the tubing empty or drained. With the equipment that is in general use it is often difficult to release the anchor which holds the tubing and it is not infrequent that the tubing cannot be drained, in which event it must be pulled while full of fluid.

A general object of my present invention is to provide a structure applicable to a string of tubing or the like to act as a drain or bleeder so that fluid can be drained from the tubing at will.

It is another object of my invention to provide a tubing drain of the general character referred to which is of such arrangement and construction that it can be operated as a jar or bumper sub to aid in dislodging or releasing an anchor or the like.

It is another object of my invention to provide a structure of the general character referred to which is under full control of the operator from the top of the well.

Another object of the invention is to provide a structure of the general character referred to which is of simple, practical construction involving few sturdy dependable parts and which is free of complicated devices or arrangement likely to fail or become fouled. A feature of my present construction is the absence of threaded parts requiring manipulation or operation in order to effect operation of the structure.

The various objects and features of my invention will be fully understood from the following detailed description of a typical preferred form and application of the invention, throughout which description reference is made to the accompanying drawings, in which:

Fig. 1 is a longitudinal detailed view illustrating the structure of the present invention coupled in a tubing with parts being shown in section and the structure being illustrated in the normal position in which it occurs as the tubing is being employed to handle or pass fluid. Fig. 2 is a view similar to Fig. 1 showing the structure in an operated position, in which case the drain means embodied

2

in the structure is open, allowing fluid to drain from the tubing. Fig. 3 is a transverse sectional view taken as indicated by line 3—3 on Fig. 1. Fig. 4 is a transverse sectional view taken as indicated by line 4—4 on Fig. 2. Fig. 5 is a transverse sectional view taken as indicated by line 5—5 on Fig. 1. Fig. 6 is a transverse sectional view taken as indicated by line 6—6 on Fig. 2. Fig. 7 is a view illustrating the stem section of the structure separate from the other elements. Fig. 8 is a view illustrating the cap of the outer or body section separated from the other elements, and Fig. 9 is a transverse sectional view taken as indicated by line 9—9 on Fig. 1.

15 The structure of the present invention can be used in various situations. However, it is most practical as applied to tubing in use in a well, in which case it is inserted in the string of tubing a suitable distance above the anchor or other device that may be employed on or in connection with the tubing. In the drawings I have shown the structure of the present invention included in a string of tubing, in which case the upper portion 10 of the tubing string is coupled to the upper end of the structure while the lower portion 11 of the tubing string is coupled to the lower portion of the structure and the structure that I have provided serves as a fluid handling coupling or connection between the tubing sections.

20 The structure of the present invention includes, generally two telescopically related tubular sections, one an outer or body section A and the other an inner or stem section B, drain means C controlled by relative movement between the sections 25 A and B preferably by relative longitudinal movement between the sections, control means D governing relative longitudinal movement between the sections operated or released by relative rotation between the sections, control means E governing relative rotation between the sections, and stop means F limiting relative rotation between the sections.

The outer or body section A in the form of the invention illustrated is the lower section of the structure and it includes, generally, a tubular body 12 carrying a cap 13 at its upper end and having a lower end portion 14 with a threaded extension 15 to which the lower tubing section 11 is connected as by means of a coupling 16, or the like. In the particular case illustrated the body extension 15 is formed separate from the other parts of the body, in which case it is suitably joined thereto, as by welding W.

The cap 13 is preferably releasably connected 55 with the upper end portion of the body 12. For

3

instance, it may be threaded thereto as for instance, threaded into the upper end of the body 12, as shown in the drawings. The cap as thus applied to the body 12 closes the upper end of a chamber X formed in or defined by the body 12. In the particular form of the invention illustrated the cap 13 has an enlarged upper end portion 17 which fits against the upper end of the body 12 when the cap is applied to the body, as shown throughout the drawings.

The inner or stem section B of the structure includes, generally, a tubular stem portion 20 slidably carried in a passage or opening 21 formed through the cap 13 concentric with an opening 22 in the body section A. The stem is provided at its lower end with an enlargement or head 23 which operates in the chamber X provided in the body 12. The upper end portion of the stem 20 projects above the cap 13 and is suitably connected with the upper section 10 of the tubing string, as by a suitable coupling 26, or the like. As shown in the drawings, the coupling 26 may be threaded to the upper end of the stem 20 and may be considered a part of the present construction, since it carries a part of the means E as will be hereinafter described.

The drain means C controls flow or passage of fluid from a central fluid carrying passage 30 that extends through the structure coupling the tubing sections 10 and 11. The drain means includes, generally, a plug 31 carried by the stem section B and cooperating with a plug opening or socket 32 in the body section A. The plug 31 is preferably in the form of a depending extension on the lower end of the head 23 provided on the stem 20 and the plug opening 32 is preferably a cylindrical central opening provided in the lower portion 14 of the body 12 to slidably receive the plug. A suitable packing or sealing means such as a packing ring 33 is preferably carried by the plug 31 to seal in the opening 32 to prevent leakage around the plug when the plug is engaged in the opening.

Engagement of the plug 31 in the opening 32 closes or cuts off communication between the central passage 30 and the chamber X in the body 12 below the head 23 on the stem 20. When the plug is engaged in the opening, as shown in Fig. 1, no fluid from the interior of the structure reaches the chamber X. However, when the plug 31 is withdrawn from the opening 32 as shown in Fig. 2, there is free communication of fluid from the interior of the structure to the chamber X. The chamber X is open to the exterior of the structure by drain ports 35 as clearly shown in Figs. 1, 2 and 4 of the drawings.

The control means D governing relative longitudinal movement between the sections normally holds the sections together or contracted, as shown in Fig. 1, in which case the plug 31 is engaged in the opening 32 and this control means is operated or is releasable by relative rotation between the body and stem sections. In the form of the invention illustrated in the drawings the control means D includes one or more depending lugs 40 on the cap 13 which lugs present downwardly facing shoulders 41 that engage or bear upon the top end or face 42 of the head 23 when the sections A and B are related, as shown in Fig. 1. In the particular case illustrated I have shown diametrically opposite depending lugs 40.

The head 23 is provided with recesses 43 that extend downwardly in it from its top face 42, the recesses corresponding in number and ex-

5

10

tent with the lugs 40 so that they receive the lugs when the lugs are moved into register with them and the sections are moved apart or are extended, as shown in Fig. 2. When the sections A and B are fully extended as shown in Fig. 2 the top face 42 of the head 23 engages or strikes the lower end 44 of the cap and if the sections are moved from the normal position to the extended position rapidly or suddenly an effective hammering action is gained when the head strikes the cap. The hammering action that is gained between the body sections A and B serves as an up jar effective in releasing or jarring loose an anchor or other device that may be employed in connection with the tubing in which present structure is incorporated.

The control means E governing relative rotation between the sections A and B may be any suitable means that will serve to releasably retain or hold the body sections A and B positioned as shown in Fig. 1. In the form of the invention illustrated in the drawings the means E involves a control collar 58, which collar is keyed to one section and releasably or frictionally coupled to the other section. The collar 58 is shown provided with a plurality of depending lugs 51 which engage in recesses 52 in the enlarged upper end portion 17 of the cap 13 when the section B is in the lowered position as shown in Fig. 1. The collar 58 is shown surrounding the coupling 26 which may be considered a part of section B and it is set on the collar by one or more set screws 53. The set screws are of such size and character as to establish a frictional engagement between the collar 58 and the coupling 26, the coupling or connection being such that when sufficient rotative strain is applied to the upper section 10 of the tubing the stem section B will turn relative to the collar 58 in order to bring the lugs 51 into register with the recesses 52.

The stop means F serves to limit relative rotation between the sections A and B and positively stops the sections in the two positions shown in Figs. 1 and 2, and in Figs. 3 and 4 of the drawings. Various arrangements and constructions may be employed in carrying out the means F. However, it is advantageous to form this means by or through one or more depending stop lugs 60 on the plug 31 to cooperate with recesses 62 in the body section A at the bottom of the plug opening 32. The stop lugs 60 and recesses 62 are arranged and related to be in cooperative engagement when the sections A and B are contracted, as shown in Fig. 1, and the lugs are disengaged from the recesses when the sections A and B are extended, as shown in Fig. 2. The lugs 60 engage or stop against the ends 64 of the recesses 62 when the structure is in the normal position as shown in Fig. 1. When the sections are rotated relative to each other from the normal position to a position where the lugs 40 register with the recesses 43, the stop lugs 60 engage and are stopped by the ends 65 of the recesses 62.

The stop means F as above described enables the operator to assure proper positioning of the lugs 40 in engagement with the face 42 of the head 23 by rotating the tubing section 10 in one direction and he is able to operate the control means E and bring the lugs 40 into a stopped position in register with the recesses 43 by rotating the tubing 10 in the opposite direction.

As a means of facilitating manufacture the recesses 62 are preferably formed in an enlargement or head 70 provided on the upper end of

the extension 15, which head occurs within the body portion 14 at the lower or inner end of the plug opening 32. In practice the body portion 14 is formed with an upwardly facing shoulder 71 against which the head rests and it is formed with a central passage 72 through which the extension 15 extends to project below the body, as clearly illustrated in Figs. 1 and 2 of the drawings.

In employing the structure that I have provided it is coupled in a string of tubing as shown throughout the drawings and when the structure is in the normal position shown in Fig. 1 the lugs 40 rest on the top of head 23 holding the sections A and B in position with the plug 31 in the plug opening 32. In this position the plug 31 cuts off flow or communication from the interior of the structure through the drain ports 36. Prior to running the structure into the well the collar 50 is set by means of the set screws 53 so that it holds the structure in the position shown in Fig. 1 against accidental release or operation. Whenever the operator wishes to operate the tool, that is, either to jar with it or to drain the tubing, he rotates the tubing section 10 causing the collar 50 to slip on the coupling 26 until the lugs 40 have been turned into register with the recesses 43, where they are stopped by the cooperation of lugs 60 with the ends 65 of recesses 62. With the parts thus positioned the operator can pick up the tubing section 10 to disengage the plug 31 from the opening 32, with the result that the structure is open to allow flow from the tubing out through the drain ports 36. As the upward movement is rapid the head 23 will strike against the cap 13 causing a jar or blow effective in releasing an anchor or other structure that may be used in connection with the tubing.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. A structure applicable to a tubing including, a tubular body section with a cap and having a lateral drain opening, a tubular stem section slidably carried in the cap and having a head within the body section, a plug carried by the stem section normally engaged in a plug opening in the body section stopping flow through the opening, a lug on the cap normally engaging the head to hold the sections in the normal position, the head having a recess adapted to receive the lug to permit relative longitudinal movement between the sections to retract the plug from the plug opening, stop means stopping the stem relative to the body with the lug engaged with the head and stopping the stem relative to the body with the lug in register with the recess, and a collar keyed to one section and frictionally coupled to the other section normally yieldingly holding the sections against relative rotation.

2. A structure applicable to a tubing including, a tubular body section with a cap and having a lateral drain opening, a tubular stem section slidably carried in the cap and having a head within the body section, a plug carried by the stem section normally engaged in a plug opening in the body section stopping flow through the opening, a lug on the cap normally engaging the head to hold the sections in the normal position, the

head having a recess adapted to receive the lug to permit relative longitudinal movement between the sections to retract the plug from the plug opening, stop means stopping the stem relative to the body with the lug engaged with the head and stopping the stem relative to the body with the lug in register with the recess, and a collar positioned on the stem section by a set screw and having a lug engaged in a recess in the body section when the sections are in the normal position.

3. A structure applicable to a well tubing including, two telescopically related tubular sections adapted to rotate and to shift longitudinally relative to each other and one adapted to be fixed to the tubing, one of the sections being a female section and the other a male section entering and terminating in the female section, drain means closed when the sections are in a normal position and adapted to open and discharge fluid from the structure when the sections are shifted longitudinally relative to each other from the normal position and including a drain port in one section only, control means within the female section adapted to releasably hold the sections against relative longitudinal movement and releasable by relative rotation between the sections, and means governing relative rotation between the sections from the normal position including a lock collar carried on the male section at one end of the female section, the collar being slidably keyed to one section and frictionally engaged with the other section to rotate relative thereto only when deliberately operated by torque applied through the tubing.

4. A structure applicable to a well tubing including, two telescopically related tubular sections adapted to rotate and to shift longitudinally relative to each other and adapted to be fixed to the tubing, one of the sections being a female section and the other being a male section entering in the female section from one end thereof and terminating therein, drain means closed when the sections are in a normal position and adapted to open and discharge fluid from the structure when the sections are shifted longitudinally relative to each other from the normal position, control means within the female section releasably holding the sections against relative longitudinal movement and releasable by rotation between the sections, and means governing relative rotation between the sections including a lock collar on the male section adjacent said end of the female section and slidably keyed to one section against rotation relative thereto and frictionally set on the other section by a set screw to rotate relative thereto upon application of a predetermined force from the tubing.
